UNITED STATES PATENT OFFICE

128,653

DESIGN FOR A LATHE BENCH

Russel E. Frushour, South Bend, Ind., assignor to
South Bend Lathe Works, South Bend, Ind., a
corporation of Indiana

Application April 17, 1941, Serial No. 100,473

Term of patent 14 years

To all whom it may concern:

Be it known that I, Russel E. Frushour, a citizen of the United States, residing at South Bend, in the county of St. Joseph, State of Indiana, have invented a new, original, and ornamental Design for a Lathe Bench, of which the following is a specification, reference being had to the accompanying drawing, forming a part thereof.

Fig. 1 is a front perspective view of a lathe bench, showing my new design;

Fig. 2 is a front elevational view thereof;
Fig. 3 is an end elevational view thereof as viewed from the right of Fig. 1; and

Fig. 4 is an end elevational view thereof as viewed from the left in Fig. 1.

I claim:

The ornamental design for a lathe bench, substantially as shown.

RUSSEL E. FRUSHOUR.
